ATTORNEY

UNITED STATES PATENT OFFICE.

HORATIO G. WEST, OF HARRISVILLE, RHODE ISLAND.

PICKER.

1,397,475.

Specification of Letters Patent.

Patented Nov. 15, 1921.

Application filed April 10, 1920. Serial No. 372,802.

To all whom it may concern:

Be it known that I, HORATIO G. WEST, a citizen of the United States, residing at Harrisville, in the county of Providence and State of Rhode Island, have invented new and useful Improvements in Pickers, of which the following is a specification.

This invention relates to the textile art, particularly to loom pickers, and has for its object the provision of a picker which is so constructed that the shuttle engaging portion and the guide rod engaging portion may be replaced when worn so as to greatly increase the length of time that the device will be capable of use, as it is well known that these portions wear out and consequently render the whole device useless.

An important and more specific object is the provision of a picker of this character which has its head formed with a socket within which is disposed a removable plug, this plug engaging the shuttle and being replaceable when worn so that it is unnecessary to replace the entire picker after extended use.

A further object is the provision of a picker which is provided with a removable sleeve which bears upon the guide rod, the sleeve being replaceable when worn.

Another object is the provision of a picker which is formed entirely of fiber, bakelite or other similar material, the advantage being that such material is very durable and will withstand great wear and the use of this material being preferable to the present construction in which raw hide is commonly employed, inasmuch as heat is generated from the friction of the picker upon its guide rod and this heat soon destroys a picker formed of raw hide.

An additional object is the provision of a device of this character which consists of the minimum number of parts and which will therefore be inexpensive in manufacture, which will be efficient and durable in use, and a general improvement in the art.

With the above and other objects and advantages in view, the invention consists in the details of construction to be hereinafter more fully described and claimed, and illustrated in the accompanying drawings in which—

Figure 1 is an elevation of the device, Fig. 2 is a longitudinal sectional view,

Fig. 3 is a front elevation, and

Fig. 4 is a rear elevation.

Referring more particularly to the drawings, the numeral 10 designates the body of the picker which is formed of fiber, bakelite or other similar material. At its top the body 10 is provided with a longitudinal bore 11 within which is disposed a removable sleeve 12 which is slidably engaged upon the guide rod 13. This sleeve is held in place by a pair of pins 14 threaded into the body. At its lower end the body 10 is provided with a socket 15 with which communicates a relatively small hole 14. Disposed within the socket 15 is a plug 17 which is held in place by a transverse pin 18. A plurality of transverse reinforcing pins 19 are provided at the upper and lower portions of the body.

In operation the picker is pushed forwardly along the rod 13 by a picker stick and is pulled back by a strap fastened to the picker and stick. The picker and strap are not shown as forming no part of the present invention and as the use of the picker is so well known. In the use of the device the plug 17 engages the shuttle and pushes the same from the shuttle box. It will be seen that the plug 17 is subjected to considerable wear but when the plug is worn it may be removed by removing the pin 18 and then inserting some suitable implement through the hole 16 and forcing the plug out, after which a new plug is inserted and the device rendered as good as new. When the sleeve 12 becomes worn the pins 14 may be removed and the sleeve removed and replaced.

While I have shown and described the preferred embodiment of my invention, it is of course to be understood that I reserve the right to make such changes in the form, construction, and arrangement of parts as will not depart from the spirit of the invention or the scope of the subjoined claim.

Having thus described my invention, I claim:

A picker comprising a body having its upper portion formed with a bore counterbored throughout the major portion of its length, a removable bearing sleeve disposed within said counterbore and adapted to slide upon a guide rod, the lower end of the body being formed with a head adapted to engage

2
a shuttle, said sleeve being provided at its uppermost and lowermost points with alined threaded holes, the upper portion of the body being provided with a threaded socket 5 registering with the lowermost of the said holes, the uppermost portion of the body being formed with a threaded opening registering with the uppermost of said threaded holes, a screw threaded through the lower-

most hole in the sleeve and engaging within 10 said socket, access to said screw being had through the uppermost hole in the sleeve and the last named hole in the body, and a second screw threaded into the last named hole and engaging within the uppermost 15 hole in the sleeve.

In testimony whereof I affix my signature.
HORATIO G. WEST.
